Assistant Examiner — Anthony Vincent Rotolo

(57) **CLAIM**

The ornamental design for a solar street light as shown and described.

DESCRIPTION

FIG. 1 is a front, right, top perspective view of a solar street light showing my first new design;

FIG. 2 is a front, left, top perspective view of first design;

FIG. 3 is a back, left, bottom perspective view of first design;

FIG. 4 is a front view of first design;

FIG. 5 is a back view of first design;

FIG. 6 is a left view of first design;

FIG. 7 is a right view of first design;

FIG. 8 is an enlarged top view of first design;

FIG. 9 is an enlarged bottom view of first design;

FIG. 10 is an enlarged view of portion 10 of FIG. 1;

FIG. 11 is an enlarged view of portion 11 of FIG. 1;

FIG. 12 is an enlarged view of portion 12 of FIG. 1;

FIG. 13 is an enlarged view of portion 13 of FIG. 3;

FIG. 14 is an enlarged view of portion 14 of FIG. 3;

FIG. 15 is an enlarged view of portion 15 of FIG. 4;

FIG. 16 is an enlarged view of portion 16 of FIG. 4;

FIG. 17 is an enlarged view of portion 17 of FIG. 4;

FIG. 18 is an enlarged view of portion 18 of FIG. 5;

FIG. 19 is an enlarged view of portion 19 of FIG. 9;

FIG. 20 is a front, right, top perspective view of a solar street light showing my second new design;

FIG. 21 is a front, left, top perspective view of second design;

FIG. 22 is a back, left, bottom perspective view of second design;

FIG. 23 is a front view of second design;

FIG. 24 is a back view of second design;

(Continued)

FIG. 25 is a left view of second design;
FIG. 26 is a right view of second design;
FIG. 27 is an enlarged top view of second design;
FIG. 28 is an enlarged bottom view of second design;
FIG. 29 is a front, right, top perspective view of a solar street light showing my third new design;
FIG. 30 is a front, left, top perspective view of third design;
FIG. 31 is a back, left, bottom perspective view of third design;
FIG. 32 is a front view of third design;
FIG. 33 is a back view of third design;
FIG. 34 is a left view of third design;
FIG. 35 is a right view of third design;
FIG. 36 is an enlarged top view of third design; and,
FIG. 37 is an enlarged bottom view of third design.
The broken lines shown on the drawings depict portions of the solar street light that form no part of the claimed design.
